UNITED STATES PATENT OFFICE

WILFRED R. WOOD, OF LONDON, ENGLAND, ASSIGNOR TO INTERNATIONAL COMBUSTION ENGINEERING CORPORATION, OF NEW YORK, N. Y., A CORPORATION OF DELAWARE

PULVERIZED-FUEL-DISTRIBUTING APPARATUS

Application filed June 16, 1925. Serial No. 37,426.

This invention relates to the distribution of pulverized fuel and is especially useful for supplying such fuel to the burners of pulverized fuel furnaces, in instances where a plurality of burners are employed in a single furnace or where a plurality of furnaces are to be supplied, each having one or more burners, or otherwise where there are a plurality of delivery points which are to be supplied from a single source.

In this art difficulties are encountered when a number of burners are to be supplied with pulverized fuel from a common source of supply, owing to the necessity for continuous feed and uniform distribution to each of the burners. Heretofore it has been necessary to provide individual feed devices for each burner which, together with the control mechanisms therefor, runs up the cost of installations to an almost prohibitive figure.

Thru my invention I aim to distribute fuel amongst a plurality of conduits in a simple manner and in such a way that continuous feed and uniform distribution are realized, hence obtaining more effective operation of the installation as a whole.

How the foregoing, together with such other objects and advantages as may herein-after appear, or are incident to my invention, are realized thru my invention is illustrated in preferred form in the accompanying drawings, wherein

Fig. 1 is an elevation view showing a general arrangement of a pulverized fuel burning installation embodying my improvements;

Fig. 2 is a plan view of the structure illustrated in Fig. 1 with some of the parts broken away and the building structure omitted;

Fig. 3 is a diagrammatic elevation view illustrating my invention adapted for use in association with a battery of furnaces; and

Fig. 4 is a plan section taken on the line 4-4 of Fig. 3.

Referring now to the drawings in Figs. 1 and 2, I have illustrated my invention in association with a furnace shaped boiler such as shown in my co-pending application, Serial No. 3,921, filed January 22, 1925, in which the fuel is admitted at each of the four

corners of the boiler furnace A, there being provided a plurality of burners at each corner arranged one above the other and having the pipes or conduits 2 leading thereto from the lower portion of the cyclone distributor or chamber 3, which will be hereinafter more fully described.

The installation includes a storage bin or hopper (not shown) for the crushed coal supply, which coal is gravity fed thru a suitable conduit 5 to the pulverizer mill 6 for pulverization. The pulverized coal is led from the mill 6 to a vertical cyclone separator (not shown), where the air and coal are separated. From the separator the coal is delivered to a pulverized coal bunker 11 from which it is discharged by the feeder 12 into the fuel lines 13 for elevation to the cyclone distributor or mixer 3 as will now appear.

The elevating apparatus includes a fan 14 having its discharge directed past the discharge outlet of the feeder 12 and having a suction inlet pipe 16.

It is pointed out that a dividing member 23 is secured to the discharge outlet of the feeder 12 from which the fuel pipes 13 lead to the distributor 3, dampers 24 being provided therein for the purpose hereinafter appearing.

The cyclone distributor or chamber 3 is constructed somewhat akin to a "cyclone separator" such as used in pulverized fuel systems, there being, however, an upstanding conical portion 25 in the bottom thereof spaced from the conical wall 26 so as to provide an annular bottom 27, adjacent which the conduits 2 are led off. The fuel on being tangentially delivered into the distributor 3 by the air blast of the fan 14 whirls around and spirals toward the bottom thereof, due to the conical lower portion, so that the fuel is evenly distributed for delivery to the burners thru the medium of the conduits 2.

This uniform distribution results from the fact that there is a peculiar uniform whirling condition set up in the bottom of the cyclone chamber. This in conjunction with the pressure secures uniform distribution with substantially uniform mixture in all of the outlets.

A certain amount of flexibility is inherent in the apparatus and additional flexibility is afforded by virtue of the separated fuel pipes 13 which makes it possible to meet varying operating conditions under proper velocity conditions to secure even distribution in the cyclone.

To make the cyclone distributor function properly, certain velocity conditions should obtain therein. The furnace, however, must be fired at all rates from zero to maximum rating, therefore, the fuel supply to the cyclone distributor must be such as will result in the maintenance of desired velocities, irrespective of the varying quantities of fuel which may be delivered over the operating range. To this end I provide the double supply line, both lines of which are used at high ratings and only one of which is used at low ratings. As can be best seen in Fig. 2, the member 23 which is secured to the discharge outlet 15 of the feeder 12 has provision for connection thereto of the two fuel lines 13.

In this connection, if a single pipe of large enough size to meet the demands at high ratings were used, proper velocity condition in the cyclone distributor would not be obtained at lower ratings.

Referring now to Figs. 3 and 4, I have illustrated my invention adapted for use in connection with a battery of vertically fired furnaces (not shown), each provided with a plurality of burners. For example, a battery of four furnaces, each having four burners, could be supplied with fuel by means of a distributor such as that shown in Fig. 3. The construction of the distributor 3' and the fuel lines 13' and dampers 24' being similar in all respects to the distributor shown in Figs. 1 and 2, with the exception that the conduits 21 leading to the burners lead out of the annular bottom 27' of the distributor 3', instead of from the bottom of the conical wall thereof, as in the other embodiment. In this instance, valves 28 are located in the conduits 2' in order that one or more may be cut out, as desired, when operating at low ratings.

Claim:

1. In a pulverized fuel handling or delivering apparatus the combination of a cyclone chamber, a plurality of conduits equally spaced about and opening from the periphery of the lower portion thereof and means for tangentially introducing powdered fuel into the chamber in suspension in a blast.

2. A cyclone distributor for a pulverized fuel system comprising a casing forming a chamber, means for tangentially introducing powdered fuel into the chamber in suspension in a blast of air and a plurality of conduits leading from said chamber, into which conduits all of the air with the fuel suspended therein is distributed.

3. A cyclone distributor for a pulverized fuel system comprising a casing forming a

chamber, means for tangentially introducing powdered fuel into the upper portion of the chamber in suspension in a blast of air and a plurality of conduits leading from the lower portion of said chamber into which conduits all of the air with the fuel suspended therein is distributed.

4. In a pulverized fuel handling or delivering apparatus the combination of a cyclone chamber, a plurality of conduits opening from the lower portion thereof and means for tangentially introducing powdered fuel into the chamber in suspension in a blast, the said chamber being otherwise closed.

5. A distributor for pulverized fuel comprising a circular chamber having a substantially vertical axis and providing an upper cylindrical section and an inverted frustoconical lower section, means for introducing powdered fuel in suspension in a blast of air tangentially into the upper section and a plurality of delivery pipes leading from said chamber with the ends thereof arranged at substantially the same vertical height and substantially equally spaced about the periphery of the lower part of the inverted frustoconical section.

6. A distributor for pulverized fuel comprising a circular chamber having a substantially vertical axis, means for introducing a mixed fuel and air stream tangentially in the upper portion of said chamber, and a plurality of delivery pipes leading from openings in the lower portion of said chamber, the said openings being arranged in substantially the same horizontal plane and being substantially equally spaced about the periphery of the lower part of said chamber.

7. A distributor for pulverized fuel comprising a circular chamber having a substantially vertical axis, means for introducing a mixed fuel and air stream tangentially in the upper portion of said chamber, a plurality of delivery pipes leading from openings in the lower portion of said chamber, the said openings being arranged in substantially the same horizontal plane and being equally spaced about the periphery of the lower part of said chamber and an upright conical member in the lower portion of said chamber with the edge of its base lying adjacent the delivery pipes.

8. A distributor for pulverized fuel comprising a circular chamber, means for introducing a mixed fuel and air stream tangentially into one end portion thereof, a plurality of delivery pipes leading from openings in the other end thereof, the said pipe openings being arranged in a plane at right angles to the axis of the chamber and being substantially equally spaced about the periphery of said chamber.

In testimony whereof, I have hereunto signed my name.

WILFRED R. WOOD. 130
